Attorney

UNITED STATES PATENT OFFICE.

LEON E. CULVER, OF BUTTE, MONTANA.

CLOTHES-WASHING MACHINE.

Application filed August 27, 1924. Serial No. 734,450.

To all whom it may concern:

Be it known that I, LEON E. CULVER, a citizen of the United States, residing at Butte, in the county of Silver Bow and State of Montana, have invented certain new and useful Improvements in a Clothes-Washing Machine, of which the following is a specification.

This invention relates broadly to an improved clothes washing machine, but it has more specific reference to a supplemental device to be used in association with a machine for the purpose of filling or draining the tub.

What I propose to do is to provide a pump having suction and discharge conduits in communication therewith, the discharge conduit being provided with a movable nozzle capable of being disposed over the tub of the machine or over a sink for discharging the water into one of these receptacles. The suction conduit is provided with a flexible hose having a nozzle to be placed into a water supply receptacle, such as a boiler, to convey the water from the latter to the tub of the machine through the pump and the discharge pipe. Other details and features of construction are embodied and these will become apparent from the following description.

In the drawing,

The single figure represents an elevational view of a clothes washing machine constructed in accordance with the present invention.

Referring to the drawing in detail, the reference character 1 designates a movably supported tub. A sink, shown in dotted lines, is designated by the character 2. Mounted on the washing machine is a conventional centrifugal pump 3, the discharge pipe 4 of which extends upwardly to a point adjacent the top of the tub. At its top, this pipe is provided with a rotatably mounted discharging nozzle 5. Intermediate its ends, the discharge pipe is provided with a bulbous enlargement 6 to increase the fluid capacity of the system. Also in communication with the pump 3 is a suction pipe 7 which leads to the top of the tub. At the end of the last named pipe, a flexible rubber hose or the like 8 is connected, this hose being provided at its intake end with a spherical apertured nozzle 9 adapted to be immersed into a boiler or other supply receptacle. Adjacent the pump, a suitable chamber forming enlargement 10 is provided. This enlarge-

ment 10, like the aforesaid enlargement 6, serves to increase the fluid capacity of the system. At its bottom, the tub 1 is provided with a valved drain 11 in communication with the pump. The pump is driven by suitable motor 12.

Assuming that it is desired to fill the tub 1 with boiling water, the nozzle 9 on the hose 8 is immersed in a boiler of water and the pump 3 is started to suck the water from the boiler through the pump and into the discharge pipe 4, whereupon it is delivered from the latter into the nozzle 5 which is then turned to the dotted line position indicated to discharge the water into the tub. At this time, the valve in the drain device 11 is of course closed. By opening this valve and starting the pump, the water may be drained from the tub and driven through the discharge pipe 4 into the sink 2 by disposing the nozzle 5 over the latter as shown in the drawing. This draining operation could also be obtained by leaving the valve in the drain 11 closed and immersing the nozzle 5 into the water in the tub and sucking it through the pipe 7 into the pump and thence through the discharge pipe. Thus, it is obvious that the device will permit water to be transferred from one receptacle to another and to obviate the necessity of placing the housewife under the strain of handling the same as is now the case. By maintaining a quantity of water in the system at all times it is rendered fool-proof and is primed and ready for immediate operation.

It is thought that the foregoing description when taken in connection with the drawing will suffice to enable a clear understanding of the invention to be had. Therefore, a more lengthy description is deemed unnecessary.

Having thus described the invention, what I claim is:

1. A clothes washing apparatus comprising a tub, a valved drain device at the bottom thereof, a centrifugal pump located beneath said drain device and in communication with the latter, a suction pipe leading to said pump, a hose carried by said suction pipe, a nozzle on the free end of said hose, a discharge pipe leading from said pump and to the top of said tub, and a second nozzle rotatably mounted on the upper end of said discharge pipe.

2. A clothes washing apparatus comprising an open top tub, a portable support

therefor, a valved drain device connected to the bottom of said tub, a centrifugal pump located beneath said tub and in communication with said drain device, a suction pipe leading from said pump upwardly along one side of the tub and above the latter, a suction hose connected to the upper end of said suction pipe, said suction hose being provided at its intake end with a nozzle, a dis-

charge pipe extending from said pump upwardly along the opposite side of the tub and above the top thereof, an angularly disposed nozzle rotatably mounted on the upper end of said discharge pipe to be positioned at will over said tub or some other form of collection receptacle. 10 15

In testimony whereof I affix my signature.
LEON E. CULVER.
